UNITED STATES PATENT OFFICE

117,187

DESIGN FOR A SET OF CARDS

Estella Stokes McCandless, Detroit, Mich.

Application July 30, 1938, Serial No. 78,968

Term of patent 14 years

To all whom it may concern:

Be it known that I, Estella Stokes McCandless, a citizen of the United States, residing at Detroit, in the county of Wayne and State of Michigan, have invented a new, original, and ornamental Design for a Set of Cards, of which the following is a specification, reference being had to the accompanying drawings, forming part thereof.

The drawings are face views of a set of playing cards, showing my new design.

The backs of the cards are conventional.

I claim:

The ornamental design for a set of cards, as shown and described.

ESTELLA STOKES McCANDLESS.
